UNITED STATES PATENT OFFICE

2,453,253

COALING CHUTE

James E. O'Brien, Cleveland, Ohio

Application December 2, 1944, Serial No. 566,289

5 Claims. (Cl. 193—18)

1

The present invention relates to a coaling chute for railway locomotives, and more particularly to a coaling chute structure which may be used in conjunction with the existing type of coaling plants for more conveniently and advantageously directing the coal from the storage bin to the tender coal box of a locomotive.

Locomotive coaling plants now generally comprise coal storage structures disposed in elevated positions relative to the tracks and they are located at one side of a track or they may extend over one or more tracks. Coal is fed by gravity from these storage structures by coaling gates which are often arranged to discharge coal transversely of the track, and open top aprons are provided for directing the coal downwardly into the locomotive tender. These aprons are incapable of directing the coal longitudinally relative to the track and, therefore, in order to properly distribute the coal throughout the tender coal box, it is necessary to move the locomotive several feet at a time two or three times during each coaling operation. This consumes considerable time and the locomotive and its equipment are subjected to considerable wearing and straining, particularly where the locomotive is attached to the train.

It is contemplated, by my invention, to provide a chute structure which may be readily attached to existing coaling plants having undercut, overcut or sidecut type gates without replacing the gates whereby the coal discharged by the usual coaling gates can be directed downwardly and longitudinally with respect to the railway track so that after the tender of the locomotive is once spotted, the stream of coal supplied to the tender can be directed throughout the length of the coal box of the tender for proper distribution of the coal without the necessity of changing the position of the locomotive. The time required for filling the locomotive tender is materially reduced and it is feasible to coal a locomotive while it is on the high speed track and attached to the train.

Another object of the invention is to provide a coal chute adapted for use with existing type of coal gates which extend laterally relative to the railway, which chute is closed and can be swung longitudinally of the railway so that the coal can be distributed throughout the tender coal box by swinging the chute.

Another object of the invention is to provide means whereby the fireman, or other attendant of the locomotive, may swing the coal chute to the desired position by mechanism located adjacent the locomotive tender.

Among the objects of my invention is the provision of an enclosed coaling chute supported for shifting movement relative to the track or longitudinal dimension of the coal box of the tender

vated coal discharging device arranged to discharge coal transversely relative to the railway track; a frame adapted to be secured on the outside of said structure adjacent the coal discharge device; a coal chute member having a coal inlet opening and a coal discharge opening arranged at substantially right angles to the plane of the coal inlet opening and a wall interconnecting said openings, said wall being disposed opposite said coal discharging device; an axle member secured to the wall of said chute member concentric with said coal inlet opening; bearing means supported by said frame for supporting said axle member; a brace member extending laterally from said axle member to said wall of said chute and attached to said wall for bracing the chute against movement in a direction longitudinally of said axle; and means for swinging said chute about the axis of said axle.

2. In a coaling plant for railway locomotives and the like, a coal storage structure having a coal gate extending laterally and downwardly; a closed coal chute having an inlet opening adapted to surround said coal gate and a discharge opening adapted to discharge coal in a substantially vertical plane, said chute including a wall interconnecting said openings and being disposed opposite said coal gate for directing coal to said outlet; and means securing said chute in position relative to said gate solely by pivotally supporting said wall of the chute on an axis extending centrally of said inlet opening.

3. In a coaling plant for railway locomotives and the like, a coal storage structure having a coal gate extending laterally and downwardly; a closed coal chute having an inlet opening adapted to surround said coal gate and a discharge opening adapted to discharge coal in a substantially vertical plane, said chute including a wall interconnecting said openings and being disposed opposite said coal gate for directing coal to said outlet; and means securing said chute in position relative to said gate substantially solely comprising a frame attached to said structure and having a beam extending in said inlet and an arm extending adjacent to the outside of said wall of said chute, an axle member extending through said wall of the chute, said axle being supported by said beam and arm.

4. In a coaling plant for railway locomotives and the like, a coal storage structure having a coal

gate extending laterally and downwardly; a closed coal chute having an inlet opening adapted to surround said coal gate and a discharge opening adapted to discharge coal in a substantially vertical plane, said chute including a wall interconnecting said openings and being disposed opposite said coal gate for directing coal to said outlet; and means securing said chute in position relative to said gate substantially solely comprising a frame attached to said structure and having a beam extending in said inlet and an arm extending adjacent to the outside of said wall of said chute, an axle member extending through said wall of the chute and connected integrally to said wall, bearings supported by said arm and beam, said axle being journaled in said bearings.

5. In a coaling plant for railway locomotives and the like, a coal storage structure having a coal gate extending laterally and downwardly; a closed coal chute having an inlet opening adapted to surround said coal gate and a discharge opening adapted to discharge coal in a substantially vertical plane, said chute including a wall interconnecting said openings and being disposed opposite said coal gate for directing coal to said outlet; and means securing said chute in position relative to said gate substantially solely comprising a frame attached to said structure and having a beam extending in said inlet and an arm extending adjacent to the outside of said wall of said chute, an axle member extending through said wall of the chute and connected integrally to said wall, bearings supported by said arm and beam, said axle being journaled in said bearings.

20 6. In a coaling plant for railway locomotives and the like, a coal storage structure having a coal gate extending laterally and downwardly; a closed coal chute having an inlet opening adapted to surround said coal gate and a discharge opening adapted to discharge coal in a substantially vertical plane, said chute including a wall interconnecting said openings and being disposed opposite said coal gate for directing coal to said outlet; and means securing said chute in position relative to said gate substantially solely comprising a frame attached to said structure and having a beam extending in said inlet and an arm extending adjacent to the outside of said wall of said chute, an axle member extending through said wall of the chute and connected integrally to said wall, bearings supported by said arm and beam, said axle being journaled in said bearings.

25 7. In a coaling plant for railway locomotives and the like, a coal storage structure having a coal gate extending laterally and downwardly; a closed coal chute having an inlet opening adapted to surround said coal gate and a discharge opening adapted to discharge coal in a substantially vertical plane, said chute including a wall interconnecting said openings and being disposed opposite said coal gate for directing coal to said outlet; and means securing said chute in position relative to said gate substantially solely comprising a frame attached to said structure and having a beam extending in said inlet and an arm extending adjacent to the outside of said wall of said chute, an axle member extending through said wall of the chute and connected integrally to said wall, bearings supported by said arm and beam, said axle being journaled in said bearings.

30 8. In a coaling plant for railway locomotives and the like, a coal storage structure having a coal gate extending laterally and downwardly; a closed coal chute having an inlet opening adapted to surround said coal gate and a discharge opening adapted to discharge coal in a substantially vertical plane, said chute including a wall interconnecting said openings and being disposed opposite said coal gate for directing coal to said outlet; and means securing said chute in position relative to said gate substantially solely comprising a frame attached to said structure and having a beam extending in said inlet and an arm extending adjacent to the outside of said wall of said chute, an axle member extending through said wall of the chute and connected integrally to said wall, bearings supported by said arm and beam, said axle being journaled in said bearings.

35 9. In a coaling plant for railway locomotives and the like, a coal storage structure having a coal gate extending laterally and downwardly; a closed coal chute having an inlet opening adapted to surround said coal gate and a discharge opening adapted to discharge coal in a substantially vertical plane, said chute including a wall interconnecting said openings and being disposed opposite said coal gate for directing coal to said outlet; and means securing said chute in position relative to said gate substantially solely comprising a frame attached to said structure and having a beam extending in said inlet and an arm extending adjacent to the outside of said wall of said chute, an axle member extending through said wall of the chute and connected integrally to said wall, bearings supported by said arm and beam, said axle being journaled in said bearings.

JAMES E. O'BRIEN.
